ATTORNEY

UNITED STATES PATENT OFFICE.

FRANKLIN H. JACKSON, OF BERKELEY, CALIFORNIA, ASSIGNOR TO BYRON JACKSON IRON WORKS, OF WEST BERKELEY, CALIFORNIA, A CORPORATION.

APPARATUS FOR SUBMARINE OPERATIONS.

No. 901,104.

Specification of Letters Patent.

Patented Oct. 13, 1908.

Application filed May 8, 1908. Serial No. 481,580.

To all whom it may concern:

Be it known that I, FRANKLIN H. JACKSON, citizen of the United States, residing at Berkeley, in the county of Alameda and State of California, have invented new and useful Improvements in Apparatus for Submarine Operations, of which the following is a specification.

My invention has reference to caissons 10 adapted to be sunk in the bottom of bodies of water for various kinds of submarine operations; and it consists in the peculiar construction of the caisson, and in the novel combination and arrangement of parts.

15 It includes a novel method of suspending the caisson, obviating the necessity of obstructive and lofty hoisting apparatus; an extendible caisson that may be rapidly assembled and occupying small space when 20 disassembled; an inner caisson which may be suspended within and raised or lowered independently of outer caisson; and in various other details of construction, as will be more fully hereinafter referred to and shown in 25 the drawings, in which—

Figure 1 is a plan or top view. Fig. 2 is a longitudinal view partially in section, on line $x-x$ Fig. 1. Fig. 3 is a section of caisson with side broken away, and showing 30 inner caisson in operating position. Fig. 4 is a side elevation of side member of caisson. Fig. 5 is a top view of side member of caisson. Fig. 6 is a section of angle iron joint. Fig. 7 is a top view of complete section. 35 Figs. 8 and 9 are modified means for securing side and back plates. Fig. 10 is an elevation of back plate. Fig. 11 is a vertical view of back plate. Fig. 12 illustrates the joint between vertical members, showing the plate 40 or bar 6^c bolted across the junction of said members.

In the following description of construction and operation, the same number will be used to designate similar members in all 45 views.

A is a float or pontoon, in which B is a well-hole, and in this well-hole is suspended the caisson C. Said caisson is supported by chains or cables 3, 3^a, 3^b, extending from the 50 lower or bottom caisson to the deck of float or pontoon A; thence over sheaves as at 4, 4^a, 4^b to a hoisting winch as at 5, or a hydraulic cylinder. The supporting chains or cables 3, 3^a, 3^b are preferably secured to the 55 vertical members 6, 6^a, 6^b (as shown at 9, 9^b

Fig. 2), said vertical members being of sufficient length to support two or more sections of the assembled plates forming the said caisson C, also showing two of the side members 7, 7^a of the caisson, and the inner caisson 60 in operative position.

In Fig. 2 the side of the float is broken away showing three assembled sections of the caisson suspended by means of the chains 3, 3^a, 3^b, and the inner caisson 8 is partially 65 extended below lower caisson C, said inner caisson 8 being supported by cables 22, passing over the upper cable sheaves 10, 10^a, and thence to the inner caisson hoisting drum 11.

Fig. 4 shows construction of the side plate 70 7 with exterior angle bars 12—12^a riveted to top and bottom edges thereof, the outer turned flanges 13 strengthening the side members 7, and forming means of detachably connecting together the plurality of sections 75 by bolts extending through said flanges 13, as shown in sectional view, Fig. 7, also showing the securing lugs 14 riveted to the side plates 7 extending to detachably connect side members 7 to vertical members 6, 6^a by means 80 of through bolt 15.

Fig. 5 is a top view of side members 7 showing connecting flanges 13, securing lugs 14, 14^a, and angular or curved form of the 85 side plate 7.

In Fig. 6 is shown a section of the joint, with connecting flanges 13 riveted to side plates 7, and through bolts 19.

Fig. 7 is a top view of a complete section 90 of caisson, showing side members 7, 7^a, back plate 16, vertical members 6, 6^a, 6^b, with securing bolts 15 and 17, and connecting flanges 13, a portion of one of said flanges broken away to show the method of securing lugs 14, and back plate 16.

In Figs. 8 and 9, the vertical members 6, 6^a, 6^b are shown varied in form, and yet within the claims of this device.

Fig. 10 is an elevation of the back plate 16 100 showing angle bars 18 riveted to top and bottom edges thereof, and forming means of detachably connecting together a plurality of members 16 by means of bolts extending through said angle bars 18.

Fig. 11 is a top view of back plate 16, angle bars 18 and bolt holes 20.

Fig. 12 shows method of securely joining vertical members by means of bars or plates 6^c bolted across the junction of said members.

The operation of the apparatus is as follows: The vertical members 6 are placed in position in well hole B supported by cables or chains 3, 3^a, 3^b secured to the lower ends 6 of said vertical members. The curved side sections 7, 7^a are bolted to said vertical members by means of the securing lugs 14, 14^a; one section of back plate 16 being secured to the vertical members 6, thus forming a complete extendible section of caisson pentagonal in form, said form adopted as offering the least resistance to rapidly flowing currents or tides. The inner caisson 8, which is of smaller outside dimensions than outer 15 caisson C is suspended by means of the supporting chains or cables 9 within caisson C. The assembled caissons are then ready to be lowered as required by means of the above described apparatus. Additional side and 20 back sections are added as required. The vertical members 6 are extendible by means of additional lengths secured thereto as shown in Fig. 12.

The inner caisson 6 is of smaller outside 25 dimensions than outer caisson C and is slideable within said caisson C permitting continuous operation while sections are being added to said outer caisson.

By the described construction of the outer 30 sections it will be seen that, although pentagonal in form, only three vertical posts are required in construction, which thus considerably reduces the cost of construction.

The guide pulleys 30 over which the chains 35 from the outer caisson pass are so located that the chains from each of the three angles are brought parallel to a common point where they are attached to a device 31, and this device has a single connection with the 40 yoke 32, or equivalent support for the pulley of the hoisting apparatus 5 so that a single rope from the hoisting apparatus, where as many multiplying pulleys 32 as may be required, serve to raise and lower the outer 5 caisson, with all portions moving in unison and vertically. The inner caisson being independently suspended within the outer one, and having an independent hoisting mechanism, it will be seen that this caisson may be 45 raised or depressed independent of the other, and that operations may be continued within the inner caisson, while the outer one is being built up or extended to suit the requirements of the work.

Having thus described my invention, what I claim and desire to secure by Letters Patent is—

1. In an apparatus for submarine operations, the combination with a float, of a vertical outer caisson supported by chains or cables secured to the bottom member of said caisson and extending to said float, and a suitable hoisting device.

2. In an apparatus for submarine operations, the combination with a float, of a ver-

tical outer caisson supported by chains or cables secured to the bottom member of said caisson and extending upward to said float, an inner caisson of smaller dimensions and slideable within said outer caisson, and supported by chains or cables extending to the float and suitable hoisting devices. 70

3. In an apparatus for submarine operations, the combination with a float, of a vertical outer caisson supported by chains or cables secured to the bottom member of said caisson, and extending upward to said float, said outer caisson being composed of a plurality of detachable sections adapted to extend from the float to the river bed. 75

4. In an apparatus for submarine operations, the combination of vertically extendible beams and side sections connecting the same, said beams of sufficient length to receive a plurality of the side sections, said sections being secured to said vertical beams by means of bolts projecting through extending flanges or lugs riveted to said side sections. 80

5. In an apparatus for submarine operations, the combination of vertically extendible beams and side sections connecting therewith said beams being of sufficient length to receive a plurality of side sections, said sections being detachably secured to said beams, by means of bolts extending through outwardly projecting flanges, and lugs riveted to said side sections. 85

6. In an apparatus for submarine operations, the combination with a float, of an outer caisson composed of a plurality of detachable sections, adapted to extend from the float to the river bed; said outer caisson supported by chains or cables secured to the bottom members of said caisson, and extending upward to said float and hoisting apparatus, 100 and an inner caisson of smaller dimensions and slideable within said outer caisson, and the inner caisson supported by chains or cables extending upward within said outer caisson to the float, and hoisting apparatus. 105

7. In an apparatus of the character described, a float having a vertically disposed pentagonal well, with an acute forward angle, a caisson formed of vertical beams at the front and the two rear angles, and side 115 and rear plates secured thereto, said caisson being movable within the well, suspending chains fixed to the lower ends of the beams, guide pulleys upon the float and a hoisting mechanism to which the chains are led to 120 be acted on in unison.

8. In an apparatus of the character described, a float with a central well and hoisting mechanism, a pentagonal caisson movable in the well, said caisson having an acute forward angle, a vertical post at said angle, and posts at the rear angles, sides bent to meet said posts, and to form intermediate obtuse angles, and angle bars riveted to the upper and lower edges of said plates. 125

9. In an apparatus of the character described, a pentagonal caisson having an acute angled front, a flat rear, and intermediate obtuse angles, vertical extensible posts at the front and rear angles, side plates bent to meet said posts and form the intermediate obtuse angles, angle bars riveted to the upper and lower edges of the plates and bolts whereby the length of the caisson 10 may be extended.
10. In an apparatus of the character described, a pentagonal caisson having an acute front angle, and a flat rear, vertical posts at the front and rear angles, side and rear plates bent to meet the posts and form intermediate obtuse angles, reinforcing angle plates secured to the top and bottom edges of the plates, and lugs by which the plates are secured to the posts.
11. In an apparatus of the character described, a pentagonal caisson having an acute front and flat rear, vertical posts at the front and rear angles, a float with a central similarly shaped open well within which 25 the caisson is movable, chains and means to secure them to the lower ends of the posts, guide and direction pulleys upon the float over which the chains pass, an attachment to which all the chains are con-

nected, and a single hoisting device with 30 which the attachment is connected.

12. In an apparatus of the character described, a float having an open central well; a pentagonal caisson having an acute angled front and flat rear, means carried by the 35 float to raise or lower the caisson in the well, an inner caisson loosely fitting and movable within the first named caisson, chains by which it is suspended, guide and direction pulleys carried by the outer caisson, and a hoisting device carried by the 40 float, with which said chains are connected.

13. In an apparatus of the character described, a float having an open central well, pentagonal caissons having acute front angles, one of said caissons loosely inclosing the other, a plurality of hoisting devices connected with said caissons whereby said 45 caissons may be independently raised and lowered within the well.

In testimony whereof I have hereunto set my hand in presence of two subscribing witnesses.

FRANKLIN H. JACKSON.
